Attorney.

UNITED STATES PATENT OFFICE

2,090,851

APPARATUS FOR COATING PIPES

Albert G. Perkins, Buffalo, N. Y.

Application May 31, 1930, Serial No. 458,481
Renewed February 28, 1936

6 Claims. (Cl. 25—38)

This invention relates to an apparatus which has been designed more particularly for coating the inner walls of pipe lines to prevent the formation of barnacles thereon.

5 One of its objects is to provide an efficient apparatus of this character which is simple and compact in construction, reliable in operation, and whose parts are so designed and arranged as to effectively apply a uniform plastic coating to 10 the inner surface of the pipe.

Another object of the invention is the provision of a coating machine of this character which is designed to travel along the surface to be treated and which is provided with revolving 15 means for delivering the coating to the surface and for gaging its thickness.

A still further object is to provide a coating apparatus having means for applying the material to the pipe surface and means for troweling or smoothing the material uniformly over the 20 surface after it is emitted from said applying means.

Other features of the invention reside in certain novel features of construction and arrangement of parts hereinafter described and particularly pointed out in the appended claims.

In the accompanying drawings:—

Figure 1 is a side elevation of my coating apparatus shown as traveling through a pipe line for treating its interior surface. Figure 2 is a 30 front view of the apparatus arranged within the pipe. Figure 3 is an enlarged central longitudinal section thereof. Figure 4 is a sectional view showing a modified form of feeding the concrete to the applicator.

35 Similar characters of reference indicate corresponding parts throughout the several views.

While my apparatus may be employed for coating different kinds of work, it has been primarily designed for coating the inner walls of pipe lines 40 with a concrete or like plastic covering, whereby a surface is provided which prevents the formation of barnacles on the wall of the pipe line. To this end, the apparatus consists, generally, of a carriage adapted to be propelled through the 45 pipe line and having a revolving means for applying the coating material on to the pipe as the carriage travels through it.

Referring now to the drawings, 10 indicates a 50 section of steel pipe through which my apparatus is designed to travel for treating or coating the inner wall of the pipe with a covering of concrete in a moist or plastic condition, it being desirable that such pipe-wall have a roughened or serrated surface. The carriage of the apparatus may be of any appropriate construction,

but preferably consists of a longitudinal frame 11 including front and rear sets of wheels 12, 12 and intermediate sets of wheels 13, the several sets of wheels being driven by an electric or air motor 14, connected by gearing 15, 16 with the driving shaft 17 of either the front or rear sets of wheels 12. Motion is also transmitted to the intermediate sets of wheels by a sprocket chain 18 which passes at its ends around sprocket wheels 19 applied to the wheels 12, while its upper and lower stretches engage sprocket wheels 20 applied to the intermediate sets of wheels 13. As shown in Figure 1, the front and rear sets of wheels 12 are smaller in diameter than the intermediate sets of wheels, so that normally, as the machine travels through the pipe, said front and rear wheels clear the pipe wall, while the intermediate wheels engage the pipe wall, these wheels being preferably provided with a rubber or like tread surface.

Surmounting the frame 10 is a platform 21 carrying depending posts 22 which telescopically engage tubular members 23 applied to the frame. Disposed substantially centrally of this platform adjacent the rear portion thereof is a longitudinally extending tubular member conduit or feed tube 24 revolvable about a horizontal axis approximately coaxial with that of the pipe and journaled in appropriate bearings 25. This feed tube is adapted to receive the wet concrete or like material to be applied to the pipe-wall and thence deliver it to a dispensing device or applicator, indicated generally by the numeral 26, which revolves with the feed tube and is designed to discharge the concrete in layer-like fashion on to the pipe as the machine travels through it. The dispensing device is located at the rear end of the feed tube, while the front end of the latter opens into the bottom of a hopper 27 containing concrete or like plastic material. The feed tube and the dispensing device may be revolved in any well known manner, say by an air or electric motor 28 carried by the platform 21 and connected by a pinion 29 with a gear wheel 30 fixed on the feed tube.

The means for feeding the concrete from the hopper 27 through the feed tube 24 and thence to the dispensing device 26 may be of any suitable and well known construction, but I prefer to employ a screw conveyor 31 extending through the feed tube and hopper and journaled at its ends in bearings 32. Motion is transmitted to the screw conveyor to propel the concrete rearwardly through the feed tube by an air or electric motor 33.

33 connected by a pinion 34 with a gear 35 fixed on the front end of the feed screw.

The dispensing device or applicator preferably consists of diametrically disposed nozzles, two 5 being shown in the drawings, each consisting of an inner tubular section 36 communicating with the outlet end of the feed tube 24 and an outer section 37 telescopically fitted over the outer end of said inner section and having its discharge end 10 preferably flared, as indicated at 38, and disposed in juxtaposition to the inner wall of the pipe, as clearly seen in Figure 2, so that as the applicator revolves the concrete is applied directly to the pipe wall. A packing 39 is arranged between the 15 bearing portions of the nozzle sections 36, 37 and a spring 40 applied to the inner section and abutting against the outer section tends constantly to urge the latter radially outward. Said outer nozzle-section 37 has a guide wheel or gage-roller 41 20 thereon which is disposed for rolling contact with the inner wall of the pipe 10 and should there be an unevenness in the pipe, the spring 40 will permit the outer section to move radially inward and will constantly maintain its flared or discharge 25 mouth in proper relation to the pipe-wall and thereby govern the thickness of the concrete applied to such wall. As shown in Figure 2 this guide wheel is so positioned that its tread surface projects laterally or to one side of the discharge 30 end of the nozzle, so that said wheel acts to clear the nozzle-mouth from any obstruction in the pipe during rotary movement of the applicator.

The provision of the telescopic nozzle-sections 36, 37 also enables the machine to be readily 35 adapted for use with pipes of different sizes. Furthermore, the discharge ends of the nozzles may be arranged in the same vertical plane or slightly staggered lengthwise of the pipe to effect the discharge of the concrete at points adjoining each 40 other.

At their trailing sides, the discharge ends of the concrete-emitting nozzles are provided with trowel-like members or blades 42 which act to spread and smooth over the concrete as it is applied to the pipe from the nozzles. Radial arms 45 interposed diametrically between these nozzles have similar members 44 applied thereto which act in conjunction with the companion members and may be staggered relatively thereto to uniformly spread the concrete in an even layer over 50 the inner wall of the pipe. The guide wheels 40, in addition to their function of guiding the nozzles, also govern the thickness of the concrete layer applied to the pipe by maintaining the discharge mouths of the nozzles a predetermined 55 distance from the inner surface of the pipe. To enable these wheels to be adjusted as desired, their brackets 45 are shiftable radially of the nozzles by means of bolts 46 engaging slots 47 in said 60 brackets, as shown in Figure 3.

If desired, air under pressure may be introduced into the concrete hopper 21 to assist the screw 31 in forcing the concrete in a compact condition to the discharge nozzles.

To permit a thorough cleaning out of the feed conduit and nozzles, I preferably provide an opening 48 at the rear end of said feed conduit and normally closed by a plug or cap 49. A hose 65 may be introduced through these openings for thoroughly washing the parts and removing any concrete therefrom.

If desired, the apparatus may be equipped with a suitable device for upsetting or roughening the inner pipe-wall so as to insure a proper anchor- 70 age for the concrete when applied on one of the

existing applicator nozzles or it may be applied to a radial arm 50 secured to the feed tube 24 to turn therewith. This upsetting device may consist of a casing 51 mounted on the outer end of the arm and having a reciprocating chisel or like 5 tool 52 operated in any suitable and well known manner to penetrate or bite into the pipe-wall and roughen it as the machine travels through the pipe, as well as clean any foreign matter therefrom, it being understood that this device is 10 located in advance of the concrete applying nozzles 36, 37, so that the surface is treated before the concrete is applied.

The radial arms 43 and 50 may likewise be 15 composed of telescopic sections, similar to those of the nozzle-sections 36, 37, to render them suitable for use with pipes of different sizes.

Instead of employing a feed screw for forcing the concrete through the conduit 24, a cylinder 20 53 may be used and substituted for the feed hopper 21, as seen in Figure 4. This cylinder has a cover 54 at its top which may be removed for charging the cylinder with concrete and air under pressure is delivered to the cylinder through a 25 pipe 55 for forcing the concrete through the conduit.

It is to be understood that my invention is not limited to the exact details of construction and arrangement of parts herein shown and described, and that various changes therein and 30 modifications thereof may be made within the scope of the appended claims without departing from the spirit of the invention or sacrificing any of its advantages.

I claim as my invention:—

1. An apparatus for applying a coating to a pipe-wall, comprising a nozzle movable circumferentially of the pipe and adapted for communication with a source of coating material, said nozzle including a radially-movable section, and a 40 guide member disposed for rolling contact with the pipe-wall.

2. An apparatus for applying a coating to a pipe-wall, comprising a nozzle movable circumferentially of the pipe and adapted for communication with a source of coating material, said nozzle including telescopically jointed sections, a 45 guide member applied to the outer nozzle-section for rolling contact with a pipe wall, and means for yieldingly urging said guide member toward 50 the pipe-wall.

3. An apparatus for applying a plastic coating to a pipe-wall, comprising a carriage movable lengthwise through the pipe, a revolving applicator for applying a plastic material to the pipe-wall, and means revolvable with said applicator and engageable with said pipe-wall for roughening 55 its surface preparatory to receiving the coating of plastic material.

4. An apparatus of the character described, 60 comprising a carriage movable lengthwise through a conduit, a revolving element mounted on said carriage to rotate in a direction circumferentially of the conduit, and scarifying means applied to said element revolvable therewith and engageable with the conduit wall for roughening 65 its surface.

5. An apparatus for applying a plastic coating to a pipe-wall, comprising a carriage adapted for movement lengthwise through the pipe in wheeled 70 contact with its bottom portion, a revolving nozzle mounted on said carriage with its axis substantially in line with the pipe-axis, means for revolving said nozzle, a hopper for the plastic material applied to the carriage, means for feeding the 75

material from the hopper to the nozzle, means revolvable about the nozzle-axis for troweling the material on the pipe-wall, and means for propelling said carriage through the pipe whereby the plastic material is applied to the pipe-wall in continuous fashion and then troweled.

6. An apparatus for applying a plastic coating to a pipe-wall, comprising a carriage having wheels thereon for guiding contact with the interior of the pipe-wall, power means for propelling the carriage through the pipe, a feed conduit mounted on said carriage, a hopper for the plastic material applied to said carriage and in operative

communication at one end with said conduit, a revolving applicator in operative communication with the other end of said conduit and in substantially axial alignment with the pipe-axis for applying the material to the pipe-wall, means for revolving the applicator, means in said conduit for feeding the material therethrough to the applicator, and troweling means revolvable about the applicator-axis for compressing and smoothing down the plastic material as it is applied to the 10 pipe-wall. 5

ALBERT G. PERKINS.
